[57] CLAIM

The ornamental design for a combination soft-sided organizer case and accordion file, as shown and described.

DESCRIPTION

FIG. 1 is a perspective view of the combination soft-sided organizer and expandable accordion type file showing my new design in a closed vertical position;

FIG. 2 is a front elevational view thereof;

FIG. 3 is a top plan view thereof;

FIG. 4 is a rear elevational view thereof;

FIG. 5 is a left side elevational view thereof;

FIG. 6 is a right side elevational view thereof;

FIG. 7 is a bottom plan view thereof; and,

FIG. 8 is a front perspective view of the combined soft-sided organizer case and accordion file with the organizer compartment and the adjustable top cover shown in open position.
